UNITED STATES PATENT OFFICE.

GARRISON BABCOCK, OF ROCHESTER, NEW YORK, ASSIGNOR TO TELECHRONOMETER COMPANY, OF ROCHESTER, NEW YORK, A CORPORATION OF NEW YORK.

TELEPHONE-SERVICE METERING SYSTEM AND APPARATUS.

1,012,793.

Specification of Letters Patent. Patented Dec. 26, 1911.

Application filed January 22, 1910. Serial No. 539,467.

To all whom it may concern:

Be it known that I, GARRISON BABCOCK, of Rochester, in the county of Monroe and State of New York, have invented certain new and useful Improvements in Telephone-Service Metering Systems and Apparatus; and I do hereby declare the following to be a full, clear, and exact description of the same, reference being had to the accompanying drawings, forming a part of the specification, and to the reference-numerals marked thereon.

My present invention has for its object to provide a metering apparatus for use in connection with the subscribers' lines of telephone exchanges for recording the service rendered by each of said circuits and in conjunction therewith the providing of the system of circuits for controlling its operation.

A further object of my invention is to provide metering devices which record the connections actually established between calling and called subscribers' circuits, and when said circuits are connected to record in given periods or divisions of time the number of minutes the connection was maintained.

Another feature of the invention comprehends an arrangement of circuits controlling the metering apparatus so that it is rendered operative, or is actuated only when a connection has been completed by the called party answering or closing his circuit.

To these and other ends the invention consists in certain improvements and combinations of parts, all as will be hereinafter more fully explained, the novel features 40 being pointed out in the claims at the end of the specification.

In the accompanying drawing Figure 1 illustrates diagrammatically two telephone circuits with the central office apparatus, 45 and metering apparatus associated with each circuit, and Fig. 2 shows a modified construction of the metering apparatus.

The metering system apparatus constructed in accordance with my present invention is adapted primarily to register the number of calls initiated by a telephone subscriber, and after the connection has been established to record the length of time consumed in despatching the message. To this end the apparatus is located at the subscriber's station, and preferably ar-

ranged in conjunction with his telephone set, the message metering part of the mechanism being adapted to be actuated into operative position manually by the subscriber and so arranged that it is operated electromagnetically only when the called subscriber answers.

In the drawings A and B indicate respectively the calling and called subscribers' stations at each of which is located the metering apparatus, that the calling party's station being shown in the operated position. The subscribers' circuits lead as usual to the tip and sleeve contacts of the central office switchboard, with which co-operate the plugs of the answering and calling cord circuits supplied with current for talking purposes.

The calling subscriber's line circuit comprises the wires 1 and 2, and the answering cord co-operating therewith is composed of the conductors 3 and 4 leading respectively to the spring contacts 5 and 6 of the listening key and normally in contact with the terminals of wires 7 and 8 leading to one side of each of the condensers C and C'. The line circuit of the answering subscriber comprises the line wires similarly indicated by 9 and 10, to which the conductors 11 and 12 of the calling cord may be connected, said conductors terminating in the contact springs 13 and 14 of the ringing key, and normally in contact with the terminals of the wires 15 and 16, leading to the other members of the condensers C and C'. Each subscriber's telephone circuit comprises the usual transmitter T, receiver R, and receiver hook H, the latter being arranged to normally open the usual line contacts when the receiver is placed thereon. At the calling subscriber's station these contacts are indicated by a and a', the former comprising the terminal of the line wire 1.

The metering or registering apparatus associated with the subscriber's telephone set preferably comprises a plurality of numbered disks, connected together by a gear train, one of which is shown and indicated by a² and provided with ratchet teeth with which co-operates a spring operated pawl a³ carried upon a polarized armature a⁴ mounted upon the frame a⁵ of an electromagnet. The coil a⁶ of the latter is shown with its terminals a⁷ connected to the wire a⁸, leading from the contact a', its opposite

extremity a^9 being connected to the wire a^{10} , which is a continuation of the line wire 2. The armature a^4 normally stands in its attracted position, but is adapted to be elevated sufficiently to cause the pawl a^3 to engage one of the teeth of the ratchet a^2 whenever the subscriber originates a call, and while it is obvious that this operation may be accomplished in various ways, I prefer to arrange the parts so that the armature will be actuated or moved into the retracted position by the release of the receiver hook. One means of accomplishing this object consists in arranging these parts in juxtaposition, and providing the armature with a tail piece a^{11} with which cooperates a pivoted dog or pawl a^{12} mounted on the inner end of the hook H , said pawl being adapted to pass out of engagement with the armature to release the latter when the hook is arrested at the limit of its upward movement.

In order to remove the impedance of the coil a^6 from the line, when it is being used for conversational purposes, I employ in conjunction with the mechanism just described, another polarized electromagnet having an armature controlling a circuit which short circuits or shunts the coil a^6 at certain times, as will be more fully explained hereinafter. This part of the mechanism comprises an electromagnet having a coil a^{13} arranged in the wire a^{10} , said coil being polarized by the magnet a^{14} , and having the armature a^{15} . The latter when moved in one direction cooperates with the contact a^{16} from which leads the wire a^{17} terminating in the contact a^{18} . Cooperating with the latter is the normally open spring contact a^{19} which is adapted to be closed when the armature a^4 is attracted. Leading from the contact a^{19} is a wire a^{20} connected to the armature a^{15} . The latter may be caused to vibrate by variations in the direction of the flow, or potential of the current supplied to the line circuit, and this movement may be also utilized to operate a registering device indicated by a^{21} , which will record the length of time the line is in use, said record being indicated in given divisions of time in accordance with the pre-determined variations of the line current.

At the central office is arranged the usual battery, indicated by X , for supplying current to the subscribers' circuits, and operating in conjunction therewith is a direct current generator Y , which is adapted to also supply current to the line, and to generate a voltage in excess of that of the battery X . The generator is provided with the brushes y and y' , one of which is connected by the wire y^2 to the wire y^3 leading from one side of the battery, and to the coil y^4 of one of the supervisory or feed relays of

the calling cord side, the other extremity of said coil being connected by the wire y^5 to the wire 16 . The calling cord circuit is completed to the battery X by the wire x , leading from the wire 15 , and in which is arranged the coil x' of the other supervisory relay of the calling cord circuit. The battery and generator are also adapted to be connected to the answering cord conductors 3-7 and 4-8. Leading from the battery X is a wire x^2 which is connected to the conductor 7, but which has interposed therein the supervising relay coil x^3 , and a normally open pair of contacts comprising the terminal x^4 and the armature x^5 , the latter being disposed in front of one of the supervising relays of the calling cord circuit, in the present instance the relay x' , and when the contacts, last mentioned, are closed it will be seen the conductor 7 is connected to one side of the battery X , and through it and the wire y^2 a connection may be traced to the brush y . The other brush y of the generator is connected to the conductor 8 of the answering cord by the wire y^6 in which is located the other supervisory relay coil y' .

The field of the generator Y is shown provided with the coil Y' , and in circuit therewith is included a source of exciting current Y^1 and a suitable form of timing mechanism Y^3 , all so arranged that the field circuit will be alternately opened and closed at given periods of time, which may be expressed in seconds, a simple means of accomplishing this object being the arrangement of the parts, as shown, which includes providing the field circuit with a set of contacts operated by a member driven by a suitable clock train.

The central office operator's telephone set comprises the receiver R^2 and transmitter T^2 connected to opposite sides of the battery X by the wires z , z' tapped onto the springs z^2 , z^3 of the listening key, which are positioned to cooperate with the springs 5 and 6 of the answering cord to supply battery to the calling subscriber for talking purposes while the operator is ascertaining the connection desired.

The battery X and the generator Y are arranged relatively to each other in such a manner that the current supplied to the lines from each of these sources will flow in opposite directions and the timing device Y^3 controls the generator in such a way that the latter alternates with the battery in supplying current to the line for equal divisions of time. Now the operating electromagnet of the message recording meter comprising the parts a^5 , a^6 are polarized in reference to the direction of the flow of current despatched by the generator Y , and the controlling relay, operating in conjunction therewith and comprising the coil a^{13} 139

and magnet a^{14} , is similarly polarized in relation to the direction of the flow of current transmitted from the battery X. It will be seen, therefore, that the armature a^4 can only be attracted by current flowing in one direction from the generator Y, and that the armature a^{15} will likewise be attracted only by current flowing in the opposite direction from the battery X. It will be understood that in place of using a generator and battery arranged for conjoint operation, two batteries or two generators may be employed for furnishing the necessary current of opposite polarity for actuating the different polarized parts of the metering apparatus.

In describing the operation of the apparatus it will be assumed in the first instance that the calling subscriber at the station A has initiated a call in the usual manner, and that the releasing of the receiver hook H caused the armature a^4 to be elevated into the position shown in dotted lines, causing the pawl a^3 to be advanced into engagement with one of the teeth of the ratchet wheel a^2 in readiness to rotate the latter one step. This elevation of the armature may have occurred when the call was initiated, or it may stand in this position as the result of the operation of the receiver hook in answering a previous call, as shown by the position of these parts at the station of the subscriber B. It is immaterial, however, when this operation of the armature occurs for when it has been once moved upwardly it is retained in this position by the ratchet wheel a^2 until retracted by its magnet to record a message, and in the arrangement of the circuits as I have shown them, the current is only transmitted to the calling subscriber's station unless for some reason it should be desired to reverse the charge, which could be done at the volition of the central office operator by reversing the answering and calling cords after receiving the necessary instructions to set up the connection.

In answering an incoming call the operator inserts the plug of the answering cord into the jack of the calling line and pressing the listening key throws the springs 5 and 6 into engagement with the contacts z^2 , z^3 . Now, should it happen that the armature a^{15} is resting in engagement with the contact a^{16} current will flow from battery through said contacts, but should these contacts, a^{15} and a^{16} , happen to be open the battery current would pass momentarily from the line wire 1 through the coil a^6 to the wire a^{10} , thence to the line wire 2 (the contacts a^{18} and a^{19} being open) and cause the armature a^{15} to engage the contact a^{16} . After the desired connection has been set up by the insertion of the plug of the calling cord into the jack of the called subscriber the listening key is released and the ringing key operated

to signal the called party, but until he responds there is no current on the line. When the called subscriber answers in, the movement of his receiver hook closes the hook contacts at his station and current passes from the battery X over the following circuit: Battery X, wire y^3 , coil y^4 , wires y^5 , 16, spring 14, cord conductor 12, line wire 10 through the telephone set to line wire 9, cord conductor 11, spring 13, conductor 15, 75 wire x coil x' to battery. The current traversing said circuit energizes the supervisory relays and the relay x' attracts the armature x^5 into engagement with the contact x^4 which permits current to be cut back to the calling subscriber A to be supplied to his end of the line alternately from the different sources of current. If at the instant the contacts x^5 and x^4 are closed the battery X is supplying the source of current for talking purposes, 85 the path of the current over this end of the line may be traced as follows: Battery X, wire y^2 , brush y' , commutator, brush y wire y^6 ; coil y^7 wire y^6 , conductor 8, spring 6, answering cord conductor 4, line wire 2, wire 90 a^{10} , coil a^{13} , wires a^{30} , a^{20} , armature a^{15} , contact a^{16} , wires a^{17} , a^{31} , a^8 , contacts a' , a , line wire 1, cord conductor 3, spring 5, wire x^2 contacts x^4 , x^5 , coil x^3 , wire x^2 to battery. At the moment the timing mechanism Y^3 95 causes the generator to supply current the latter flows in the opposite direction over the circuit, just described, causing the contacts a^{15} and a^{16} to be opened, whereupon said current passes through the coil of the electromagnet a^6 by passing over the wires a^8 , a^7 , to coil a^6 , thence by wire a^9 to wire a^{10} (the wires a^8 and a^{10} being continuations of the line wires 1 and 2.) The energization of the electromagnet a^6 by current of the proper 100 polarity causes the armature a^4 to be attracted to actuate the message meter a^2 and close the contacts a^{18} and a^{19} . The latter when closed short circuits the coil a^6 thus removing its impedance from the line and current for talking purposes, if thereafterward transmitted from either of the two sources over the cord conductors, to the line wires of the calling subscriber's station from which point it may be traced as follows: 11 Line wire 1, contacts a and a' wires a^8 , a^{31} , a^{17} , contacts a^{18} , a^{19} , wires a^{20} , a^{30} , a^{10} , coil a^{13} , line wire 2. The current flowing over this circuit periodically in opposite directions causes the swinging of the armature a^{15} 12 and this movement may be employed, as before described, to actuate the meter a^{21} for recording in units of time the total time the line is in service.

It will be noticed that only one source of current, the battery X, is connected to the answering subscriber's circuit, and that for this reason the polarized controlling member of the metering apparatus of this circuit causes the operation of its armature b^{15} in 1

one direction and the current being unvarying holds it closed against the contacts b^18 to shunt the coil b^6 during the time conversation is being held, or the answering subscriber's line is in use.

In the arrangement of the parts described we find two electromagnets which are oppositely polarized to respond to current flowing in opposite directions. One of these 10 magnets operates the message meter a^2 and may be termed the major magnet, the other magnet operating the contacts of the shunt circuit leading around said magnet, may be called the minor or controlling magnet. The 15 latter may be a separate coil inserted in the instrument circuit as shown in Fig. 1, or it may be formed of one of the induction coils of the telephone set, as indicated by a^{190} in Fig. 2. In such an instance the 20 armature a^{150} is polarized as before described to respond to current of the opposite polarity from that employed for actuating the armature a^{40} of the message meter magnet a^{60} , and said armature a^{150} controls 25 the branch or shunt circuit for cutting out the coil a^{60} by coöperating with the contact a^{160} .

I claim as my invention:

1. The combination with a telephone circuit supplied with the ordinary talking current and a pole changer for alternating the direction of flow of said current, of two electromagnets comprising coils arranged in the telephone circuit, said magnets being oppositely polarized, a message meter actuated by one magnet, a time recording meter operated by the other magnet, means for short circuiting the coil of the first mentioned magnet and means for varying the 40 changes in the direction of flow of the current periodically.

2. The combination with a telephone circuit supplied with ordinary talking current and means for changing the direction 45 of flow of the current periodically, of metering mechanism comprising a device for registering connections set up and a recorder for measuring the length of time the circuit is in use, separate polarized electromagnets for actuating the connection 50 registering device and the time recorder, both arranged in the telephone circuit and means for shunting the electromagnet of the connection register upon its operation.

55 3. The combination with a telephone circuit supplied with ordinary talking current and means for changing the direction of flow of the current periodically, of metering mechanism comprising a connection establishing register and a time recording register, separate polarized electromagnets comprising coils arranged in the telephone

circuit for actuating the connection register and time recording register, a branch circuit for shunting the connection register 65 magnet coil having two sets of contacts one set being adapted to be closed upon the operation of the last mentioned magnet and the other adapted to be closed upon the operation of the time registering magnet. 70

4. The combination with a telephone circuit, a source of current therefor and means for periodically alternating its direction of flow, major and minor electromagnets having armatures, said magnets being polarized 75 to attract their respective armatures when energized by current of opposite polarity, the armature of the minor magnet being also capable of repulsion when its magnet is energized by current of one polarity, of 80 means for normally setting the armature of the major magnet in retracted position and a message registering device operated thereby, a time service meter operated by the movement of the armature of the minor 85 magnet and a branch circuit leading from the telephone circuit around the major magnet having contacts adapted to be closed by either of the two armatures when they are attracted. 90

5. The combination with a telephone circuit having an inductive type telephone set connected thereto comprising primary and secondary windings, and a pole piece adapted to be magnetized by said windings, of an 95 electromagnet arranged in the telephone circuit, said pole piece and magnet being oppositely polarized, a message meter operated by the magnet, a time recording meter operated by the pole piece, and means for short 100 circuiting the magnet coil, a source of current, a pole changer and means for periodically varying the changes in the direction of flow of the current over the telephone circuit. 105

6. The combination with a telephone circuit having an inductive type telephone set connected thereto comprising primary and secondary windings, and an armature for the pole piece, of an electromagnet arranged 110 in the telephone circuit, said pole piece and magnet being oppositely polarized, a message meter operated by the magnet, a time recording meter operated by the pole piece armature and a short circuit for the magnet 115 having contacts controlled by said armature, a source of current, a pole changer and means for changing the direction of flow of the current over the telephone circuit.
